UNITED STATES PATENT OFFICE.

RUDOLF R. KARICH, OF NEW YORK, N. Y., ASSIGNOR TO THE AMERICAN TAXIMETER COMPANY, OF NEW YORK, N. Y., A CORPORATION OF NEW YORK.

HUB-ODOMETER DRIVE.

1,368,504.

Specification of Letters Patent. Patented Feb. 15, 1921.

Application filed March 22, 1919. Serial No. 284,419.

To all whom it may concern:

Be it known that I, RUDOLF R. KARICH, a citizen of the United States, residing at New York, in the county of New York and 5 State of New York, have invented certain new and useful Improvements in Hub-Odometer Drives, of which the following is a specification.

This invention relates to hub-odometers, 10 and has special reference to an improved coupling or drive connection between the register operating means and the wheel axle.

To this end the invention contemplates a simple device which may be readily fitted to 15 a suitable element of the register support, in such a manner that the fitting of the odometer to the wheel hub will be greatly facilitated. That is to say, the invention contemplates a simple and practical device 20 which may be secured to a conveniently accessible or exposed part of the register support, whereby when the odometer casing is fitted to the wheel hub, a positive and reliable connection will be automatically formed 25 between the stationary nut on the axle of the wheel and the register supporting and operating means. While various expedients have been heretofore adopted for this purpose, they frequently present considerable 30 difficulty in making the installation, because of the fact that it is difficult to properly locate the parts which interengage, on account of the same being obscured from view when the odometer casing is fitted over the 35 end of the hub.

A further object of the invention is to provide an economical coupling or connector unit which may be readily made from stamped metal, and easily assembled, while 40 at the same time being thoroughly reliable and efficient under all conditions of use.

With the above and other objects in view which will readily appear as the nature of the invention is better understood the same 45 consists in the novel features, combination and arrangement of parts hereinafter more fully described.

A preferred and practical embodiment of the invention is shown in the accompanying 50 drawings in which:

Figure 1 is a vertical sectional view of a hub-odometer showing the arrangement of parts and location of the present drive connection or coupling.

Fig. 2 is a perspective view of the coupling. 55

Fig. 3 is a detail perspective view of a modified form of interlocking connection between the head of the connector arm and the slotted end of the guide member. 60

Similar references designate corresponding parts throughout the several figures of the drawings.

The invention is applicable to hub-odometers of different construction, but to illustrate one practical application there is shown in Fig. 1 a type of odometer in practical use. Referring to Fig. 1 it will be observed that the usual hub-odometer casing A which is fitted to the wheel hub houses 70 therein a stationary register unit B whose rotary base C has a recess at one side thereof for accommodating the disk D. This disk is fastened to the register supporting means journaled in the base C, and because the casing A and base C rotate with the wheel, and the register unit must remain stationary, it is necessary to connect the register supporting means with the wheel axle or nut carried thereby. This connection may be reliably 80 established by the drive connection or coupling proposed by the present invention which is intended to be carried by the disk D and engage with the stationary lock nut E on the axle F, as shown. 85

By reference to Fig. 2 of the drawings it will be observed that the said connector unit includes an attaching base portion 1 adapted to be riveted or otherwise rigidly secured to the disk D, and said base has formed therewith the oppositely disposed radial extensions 2 and 3, the former being bent at right angles to provide a guide fork 4 having the slot 5, while the latter is provided with the opposite struck-up ears 6-6. These ears 90 constitute a supporting bracket for a connector arm 7, the lower end of which may also be provided with the offset ears 8 adapted to fit between the ears 6 and pivotally secured therebetween by the pin or 95 shaft 9.

In connection with the mounting of the connector arm 7 between the bracket ears 6-6, it will be observed that the pin 9 is spaced at a sufficient distance away from 105 the face of the extension 3, whereby the end 10 of the arm below the pivot will constitute an abutment or stop to prevent the con-

ector arm from falling below center. In other words there is sufficient clearance provided between the lower end of the arm 7 and the face of the extension 3 to permit the 5 connector arm to assume an outwardly inclined or oblique position with reference to the face of the attaching base and its extensions. For the purpose of maintaining this relation of the arm to the base and also providing the resilient driving connection which is necessary to take care of any idle play between the axle and hub, the arm 7 has riveted thereto at 11 a flat leaf spring 12 which bears against the face of the attaching 10 disk to yieldingly maintain the connector arm in its outwardly inclined position.

The upper end of the connector arm 7 is provided with an offset and angularly disposed head or key portion 13 which is 15 adapted to have a guiding engagement in the slot 5 of the angularly disposed forked end of the extension 2. In the normal condition of the unit the rear edge of the head 13 rests at the mouth of the slot 5, but when 20 the arm is placed under tension as during installation or by side thrust of the axle with reference to the hub the head may ride farther back into the slot which will have the effect of steadyng or stabilizing the 25 connection between the axle and the register operating mechanism, and prevent undue twisting strain being imposed on the pivot pin.

As shown in Fig. 1 the head or key 13 is 30 adapted to fit in a slot or castellation S in the face of the nut E, and when the head of the connector arm is engaged in said slot a resilient sliding connection is provided between the lock nut fast on the axle and the 35 register operating mechanism.

From the foregoing it will be apparent that the structural features of the connector unit are such that the same may not only be readily fitted to the disk of the supporting 40 instrumentalities for the register, but also the fitting of the entire hub-odometer assembly to the wheel hub is greatly facilitated. That is to say, after the unit has been secured to the disk D and the hub-45 odometer assembly is being applied to the wheel hub, the outer edge of the head 13 will yieldingly bear against the surface of the nut, until the rotation of the casing brings the head in position to register with 50 one end of the slot S. When registry takes place the head or key 13 will snap into the slot and the driving connection is completed although obscured from view.

Fig. 3 of the drawings shows a modified 55 form of interlocking connection between the head 13^a of the connector arm 7 and the guide member 4^a. In this form of the device it is proposed to make the slot 5^a closed at the front end to provide a transverse 60 abutment web 14, whereby an offset stop

projection or ear 15 formed at one corner of the head 13^a, will prevent the connector arm swinging forward too far on its pivot. That is to say, it is proposed to form the head 13^a with an integral projection which 70 will have a free guiding engagement in the slot but will not be able to escape from the same, thereby always maintaining the correct guiding function of the guide member 4^a with reference to the head. Furthermore, 75 it is to be observed that the head 13^a has pressed therein an intermediate reinforcing rib 16 the grooved side of which is shown in Fig. 3 and which gives the same added strength and reinforcement against being 80 bent or deflected from its correct position. When the head 13^a is interlocked with the slot S of the nut E, it is subjected to more or less transverse strain, and to meet this condition it is desirable to reinforce the 85 head by the rib thereof as shown.

The construction shown in Fig. 3 not only gives the added advantage of a reinforced head, but also by reason of the projection 15 being prevented from leaving the slot 5^a 90 by the web 14 at the end thereof, it is impossible for the connector arm 7 to be twisted about on its pivot in case of the malfunctioning of any of the parts of the register mechanism or drive connections.

It is thought that other features and advantages of the device will be apparent to those skilled in the art without further description.

I claim:

1. An axle coupling unit for hub-odometers consisting of a base for attachment to a stationary part of the odometer, and a spring-pressed connector arm pivotally supported at one end in a fixed location on the 105 base and having axle-part engaging means at the other end.

2. A driving connection for hub-odometers consisting of an attaching base, radial extensions formed from said base, and a 110 spring pressed connector arm pivotally carried by one of said extensions and having a guiding engagement with the other.

3. A driving connection for hub odometers comprising an attaching base carrying 115 a pivot pin and a single spring pressed connector arm having a non-shiftable pivotal mounting on said pin at one end and its opposite free end adapted for engagement with an axle part.

4. A driving connection for hub-odometers consisting of an attaching base, a pin carried by the base and arranged in a plane parallel thereto, and a connector arm having an offset axle-part-engaging key at one 125 end while the other end is mounted on said pin.

5. A drive connection for hub-odometers consisting of an attaching base, radial extensions formed from said base, one of said 130

- extensions having an angularly disposed slotted portion, and other of said extensions having bracket ears struck-up therefrom and a spring pressed connector arm pivotally mounted between the bracket ears and having a guiding engagement in the slotted portion of the other extension.
6. A drive connection for hub-odometers consisting of an attaching base, opposite 10 radially disposed extensions therefrom, a supporting bracket formed at the end of one of said extensions, a guide member formed at the end of the other of said extensions, a connector arm mounted on a pivot arranged 15 in said bracket and spaced from the face of the attaching base, the end of said arm extending beyond the pivot to constitute an abutment for engaging with the face of the attaching base, a leaf spring carried by the 20 intermediate portion of the arm and bearing against the face of the attaching base, and an angularly disposed head portion formed from said arm and interlocked with the said guide member.
- 25 7. A drive connection for hub-odometers consisting of an attaching base, radial extensions formed from said base, a connector arm carried by one of said extensions, and a guide member formed at the end of the other 30 of said extensions and having a slot, and a

fixed abutment engaging head carried by said connector arm and having an off-set projection for engaging in said slot.

8. A drive connection for hub-odometers consisting of an attaching base formed with 35 radial extensions, a connector arm pivotally connected to one of said extensions and having an integral reinforced head portion, a knob projecting from said head portion, a slotted guide member formed at the end of 40 the extension opposite that carrying the connector arm, the slot of said member being closed at its outer end to provide an abutment adapted to be engaged by said knob 45 on the head.

9. A driving connection for hub-odometers consisting of a base for attachment to an operative element of the register, and a spring pressed connector arm pivotally mounted at one end on said base whereby its 50 opposite free end may oscillate in the arc of a circle for yieldingly engaging with an axle part.

In testimony whereof I hereunto affix my signature in the presence of two witnesses. 55
